Primary Examiner — Joseph Kukella
Assistant Examiner — Arva P Adams(57) **CLAIM**

The ornamental design for a jug, as shown and described.

DESCRIPTIONFIG. 1 is a front and top perspective view of a first embodiment of a jug, showing my new design;
FIG. 2 is a rear, and bottom perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof;
FIG. 8 is a bottom plan view thereof;
FIG. 9 is a front and top perspective view of a second embodiment of a jug.FIG. 10 is a rear and bottom perspective view thereof;
FIG. 11 is a front elevation view thereof;
FIG. 12 is a rear elevation view thereof;
FIG. 13 is a left side elevation view thereof;
FIG. 14 is a right side elevation view thereof;
FIG. 15 is a top plan view thereof; and,
FIG. 16 is a bottom plan view thereof.

The broken lines in the figures illustrate portions of the article that form no part of the claimed design.

1 Claim, 16 Drawing Sheets(56)
